UNITED STATES PATENT OFFICE.

WILLIAM F. STONE, OF PORTLAND, MAINE, ASSIGNOR TO NATIONAL METAL SEAL CORPORATION, A CORPORATION OF MAINE.

CLOSURE FOR CONTAINING VESSELS.

1,192,135.

Specification of Letters Patent. Patented July 25, 1916.

Application filed January 20, 1915. Serial No. 3,200.

To all whom it may concern:

Be it known that I, WILLIAM F. STONE, a citizen of the United States, residing at Portland, county of Cumberland, State of Maine, have invented certain new and useful Improvements in Closures for Containing Vessels, of which the following is a specification.

This invention relates to closures for containing vessels and particularly to a one piece closure for a vessel having a flanged neck or nozzle.

The closure of my present invention is especially applicable to that class of containing vessels which are to be used from time to time after their initial opening. One objection to the closures now in use on this class of receptacles is that the cap is apt to drop down over the nozzle mouth when pouring and thus interfere with that operation or that when swung up it drops back too far and sometimes becomes disengaged from the flanged vessel neck. To the end therefore of providing a closure of this general type which can not drop down over the vessel mouth when pouring and can not accidentally disengage from the flanged vessel neck in its opening movement, I have devised my present invention. I will discuss the form shown as illustrative of the principles of my invention, first generally to set forth the principles involved.

In the form shown, the depending skirt of the cap has a hinge lug which is initially crimped under a shoulder about the nozzle mouth. This shoulder is preferably formed as a continuously recessed rim by upsetting the metal of the vessel mouth. In the opening movement of the cap, the hinge lug turns on the shoulder as a pintle and begins to bind over its inner edge to hold the cap out of the way in pouring and to lock it against accidental dislodgment from the vessel. The hinge lug may be crimped under the shoulder of the nozzle at any point about the circumference thereof and may be combined with a plurality of locking lugs formed on the circumferential skirt of the cap and adapted for engagement with said continuously recessed rim to lock the cap in sealing position over the delivery opening of the nozzle. The locking lugs are adapted to be pried outwardly from the shoulder sufficiently to permit opening of the cap by a swing thereof upwardly and away from

the delivery opening. Where the container is to be used from time to time after its initial opening, an uncrimped locking lug is provided which frictionally engages the flange of its nozzle and acts as a temporary lug.

The construction and operation of my invention will be more fully disclosed in the specification which follows.

In the drawings forming a part of that specification I have shown as an illustrative embodiment a form of closure which has proven satisfactory in practice and well adapted to the requirements of manufacture.

Throughout specification and drawings like reference numerals are correspondingly applied, and in these drawings: Figure 1 is a rear view of a closure in accordance with my invention, applied to a flanged container nozzle in sealing position. Fig. 2 is a front elevation thereof. Figs. 3 and 4 and 5 are enlarged partial sections illustrating the locking action indicated hereinbefore. Fig. 6 is a partial underneath section of the nozzle showing the cap closed, and Fig. 7 is an underneath view showing the cap fully opened.

I have indicated at 1 a vessel mouth or nozzle which is preferably made of sheet metal or other suitable material. The nozzle has a continuously recessed rim about its mouth formed by upsetting the edge of the mouth. This leaves a horizontally disposed annular flange 2 which affords a flat seat for the seal or pack 2¹. The flange 2 is bent downwardly at substantially right angles to provide a continuous circumferential skirt 3 disposed in a vertical plane substantially parallel to the nozzle 1. The skirt 3 is bent inwardly at 3¹ and extends as the arc of a circle for a slight distance, and is then deflected tangentially inwardly and upwardly and extends as an upwardly directed, continuous portion 3² terminating in an edge 4, surrounding the mouth. The portion 3² provides a continuous pintle over which the hinging lug of the closure may be crimped at any point about its circumference. This portion is spaced from the nozzle so as to leave a continuous recess 4¹ toward which the inner edge of the hinge lug of the closure moves when the closure is swung to fully open position.

The closure comprises a cap 5 overlying the delivery opening 6 of the nozzle and

carrying the pack 2¹ which seats tightly against the flat rim 2 of the nozzle when the container is sealed. The cap 5 has a continuous pendent skirt or flange 1 inclosing the pack 2¹ and partially overlying the vertical overhang 3 of the nozzle. On one side of the cap and depending from the lower edge of the flange 1 is a hinge lug 9. The lug 9 is adapted to be bent up under the curved portion 3¹ of the nozzle 1 and to be clenched under said portion at any point about its circumference so as to form a permanent hinge. The lug turns on the portion 3¹ as a pintle in the opening and closing movement 15 of the cap.

The hinge lug consists of a relatively broad base portion formed as an extension of the pendent flange 1 curved concentric with the outer edge of the nozzle and fitting thereon when the cap is in closed position. The lug has an abrupt shoulder 9¹ at each 20 end of its base and tapers inwardly and terminates in a resilient pointed tip disposed under said rounded portion and adapted 25 to ride over said rounded portion in the opening movement of the cap and onto the tangential portion, and be drawn down against the edge 4 thereof by the arch of the base portion. In the opening movement of 30 the cap the lug moves upwardly around the portion 3¹ and over the edge 4 thereof and tends to ride into the recess 4¹ between said portion 3¹ and the overhang 3 of the rim. As the cap approaches its fully opened position, the lug rides over the edge 4 and in 35 the further opening movement of the cap the lug is sprung and its tip end drawn down over the edge 4 with a tight bind by the arch of its base portion.

The action of the hinge lug in the opening movement of the cap is illustrated in detail in Figs. 3, 4 and 5, wherein the successive positions of the lug during the successive phases of opening movement have 45 been shown on a slightly exaggerated scale. Referring first to Fig. 3, wherein the position which the lug occupies when the cap is seated has been indicated, the free end of the lug is represented as conforming closely 50 to the curvature 3¹ of the flange 3. As the cap opens, the tip end of the lug tends to follow the normal truly circular path indicated in dotted lines, Fig. 4, provided for it by the truly circular curvature 2¹, but is 55 deflected as it rides upwardly along said portion into the full line position by the tangential portion 3² of the flange. This produces a stress on the tip end of the lug which, having a greater degree of resiliency 60 than its base portion, yields inwardly and downwardly, and is sprung over the portion 3². This tendency on the part of the lug to spring out is further augmented by the binding action of the cap over the edge of 65 the flange 3 (indicated at 3^a in Fig. 4). In

the further opening, the cap is drawn down tightly over the edge 4 of the portion 3². This final position of the lug is indicated in Fig. 5 wherein the tip end of the lug is represented as having ridden over the edge 4 and outwardly toward the overhang, and as being tightly engaged over said edge. The opening movement of the cap is finally stopped by the shoulders 9¹ of the lug binding against the curved portion 3¹ of the flange 3. At this phase, therefore, both the tip and the base of the lug are engaged with the shoulder so that the cap is tightly held in fully opened position. This action is further illustrated in Figs. 6 and 7, 80 wherein the externally convexed and internally concaved container rim and the two positions of the lug relative to said rim corresponding to the closed and open positions of the cap, are indicated. In the closed position of the cap, the concaved lug conforms to the external convexity of the container rim, as shown in Fig. 6. As the cap opens, the lug moves inwardly so that when the cap is fully opened the lug is no longer in 85 a position of conformity to the convexity of the container rim but has assumed a position of opposed concavity to the concavity of the edge 3¹ of said rim, as shown in Fig. 7, thus securing the resilient effects of the 95 arched portions under pressure.

The initial sealing of the container is effected by one or more locking lugs 10 struck from the metal of the flange 2 on the side of the cap opposite the hinge lug 9. The 100 lugs 10 are adapted to be clenched under the shoulder 4 when the container is initially sealed. In opening the container for the first time a suitable opening implement is inserted under the lugs 10 to spread or pry 105 them outwardly from the nozzle. The cap may then be swung back to uncover the delivery opening.

Where the container is to be used from time to time it is desirable that means be 110 provided for temporarily locking the cap in sealing position. This is effected in the present invention by an uncrimped locking lug 11 which is formed as a relatively short, downward extension of the skirt 7 and is 115 preferably disposed between the pair of locking lugs 10. When the cap is initially sealed, this lug engages the flange 3 to assist the locking lugs in sealing the container. After the container has been initially 120 opened, this lug is usually sufficient to temporarily lock the cap in closed position.

After the container has been initially sealed by crimping the locking lugs under the shoulder 4 the lugs are given the form 125 best illustrated in Fig. 2. After crimping, each lug has an outwardly arched portion 12, extending in the direction of circumference of the flange 3. When the cap is snapped down into closed position, the lower 130

edge of the arch engages the flange 3 at the point 3¹ where said flange is turned upwardly to form the portion 3². Below the arched portions 12 the lugs are deflected 5 slightly outwardly to provide a somewhat elongated extension under which the opening implement may be inserted in prying open the lugs.

The device of the present invention affords a tight permanent or semi-permanent seal which can be produced inexpensively and in which the liability of the cap interfering with the pouring or falling away from the container is wholly obviated.

Various modifications in the form and construction of my device may obviously be resorted to if within the limits of the appended claims.

What I therefore claim and desire to secure by Letters Patent is:

1. In combination with a container having a curved shoulder portion, a cap having a hinge member disposed for pivotal engagement with said shoulder, said member having an arched basal portion curved substantially concentric with said curved portion of the shoulder and terminating in a deformable tip portion disposed to ride over said curved portion in the opening movement of the cap and to be drawn downwardly over the edge of said curved portion by the arch of said basal portion.

2. In combination with a container having a shoulder including a portion extend-

ing substantially as the arc of a circle and a portion extending substantially tangentially thereto, a closure having a hinge member bent in substantial conformity to said arcual portion of the container shoulder and disposed to normally conform to said arcual portion, but deflected into a position of non-conformity by said tangential portion in the opening movement of the closure wherein it binds over the edge of said tangential portion.

3. In combination with a container having a shoulder about its mouth, said shoulder having a circularly curved portion terminating in an edge portion extending substantially tangentially from said curved portion, a closure disposed to cover the mouth of said container, and a hinge member on said closure having an arched basal portion and a deformable tip portion normally disposed in a position of substantial conformity to said curved portion of the container shoulder and deflected by said tangential portion of said shoulder out of its normal position of conformity to a position of non-conformity in which it binds over the edge of the tangential portion.

In testimony whereof I affix my signature in presence of two witnesses.

WILLIAM F. STONE.
